UNITED STATES PATENT OFFICE.

CHARLES F. DE CORSE, OF LOS ANGELES, CALIFORNIA.

AUTOMATIC PUMP ATTACHMENT.

Application filed February 9, 1926. Serial No. 86,970.

The present invention relates to deep well pump attachments, and pertains more particularly to devices for attaching the pump rods to the plunger.

- 5 It will be understood in the consideration of this invention that the usual deep well pump outfit includes a string of tubing having a pump casing at the lower end, in which casing there is provided a reciprocal plunger.
10 The plunger is raised and lowered in its pumping action by means of a string of rods leading from the plunger to the surface of the ground. In raising the plunger for inspection or repair, at the end of the
15 rods, the plunger is apt to be marred in being pulled through the tubing. Likewise in lowering the plunger again it may become damaged, and it is difficult to properly assemble the plunger in the casing under
20 such conditions.

Therefore, when such outfits were first put into general use, a demand was created for a device which would partially or completely obviate such difficulties. This demand was partially met by sundry devices which permitted of lowering the plunger in assembly with the jacket, at the end of the tubing, and then subsequently lowering the rods. Said devices automatically attach
25 the rods to the plunger when properly lowered, but do not ordinarily provide for disengagement of same except above the ground. Such devices have been improved upon to some extent so that they may be
30 disengaged by backing off, or unscrewing the rods, but this procedure is impractical in the case of long strings of rods. Many rod strings are over four thousand feet in length.

35 It is therefore an object of this invention to provide a practical device for both attaching and detaching the rods and plunger without removing the plunger from the casing.

40 Another object of the invention is to provide for using a plunger which is of larger diameter than the inside diameter of the tubing, whereby production may be increased in the case of a given size of tubing.

45 Another object is to provide for disengaging the rods from the plunger temporarily in case it is desired to agitate the fluid in the tubing without operating the plunger.

50 Another object of the invention is to provide an attachment of the class described which will permit of the weight of the rods

forcing the plunger downwardly without disconnection of the plunger and rods.

In carrying out my invention I provide means carried by the pump and interlocking means carried by the plunger whereby the rods are moved downward until said means interlock. The rod string is raised slightly so that the weight of the plunger is carried by the rods. In order to again disengage the rods from the plunger, when desired, said means provide for disengagement by continuing downward movement of the rods and a quick upward movement. In order to prevent disengagement accidentally, I provide for resisting rapid downward movement of the rods relative to the plunger, while permitting of slow downward movement of the rods with regard to the plunger. Thus, in the space of time allowed for each down stroke of the plunger, the rods cannot become accidentally disengaged from the plunger, but when it is intended that the rods shall become disengaged, the full weight of the rods is caused to slowly move the rods relative to the plunger, so that they may become disengaged.

55 Various embodiments and combination of parts may be employed for carrying out my invention, and I have illustrated in the accompanying drawings one practical embodiment of my invention, which embodiment is described in the present specification, so that those skilled in the art will be enabled to 60 carry out my invention.

In said drawings:

Figure 1 is a vertical section of said embodiment, in normal pumping position.

Figure 2 is a similar view of a portion 65 thereof showing the disposition of the parts just prior to disconnection of the rods and plunger.

Figure 3 is a view in elevation of the said embodiment; showing it attached to a pump 70 plunger within a pump casing; the casing being shown in vertical section.

Figure 4 is a cross section on a line 4—4 of Fig. 1.

More specifically, 6 indicates a tube having a bore 7 open at the upper end, as at 8, and closed at the lower end as at 9. At the lower end of the interior of tube 6 a stem 10 rises a suitable distance above the closed portion 9. The interlocking means provided, consists of inwardly bent integral spring fingers 11, carried by the tube, and

a mandrel 12, adapted to be attached to the pump rod 14, as by coupling 15.

The mandrel is provided with a head 16, having a shoulder 17 and a pointed end 18, movable to force the fingers apart and to assume the position shown in Fig. 2. Said mandrel, at a point well above the head, carries a stop 19. Loosely fitted around the mandrel, there is provided a slideable ring 20, which cannot move below the head 16, or above the stop 19. The ring is so arranged that by lowering the rod, the stop of the mandrel will force the ring between the fingers to hold them spaced apart, as shown in Fig. 2. Obviously, the interlocking of the head of the mandrel and the ends of the fingers will provide for raising the plunger 21 by the rods. The tube 6 is provided with a threaded socket 22^a whereby it is screw threaded to a cage 22, such as is commonly provided at the top of deep well pump plungers. It will also be apparent that by dropping the pump rod to force the ring into position between the fingers, the mandrel 25 may be withdrawn from the tubing without interference on the part of the said fingers, particularly since the ring is of larger diameter than the largest part of the head.

While this device provides for attachment and detachment of the rods and plunger, it is not complete for the purpose in cases where the plunger does not drop as fast as the rods descend. To prevent upward movement of the mandrel with regard to the tube, under normal pumping conditions, I provide a piston 25 fitting closely to the bore of the tube and providing a practically fluid tight space 26, which decreases in volume as the piston is moved downwardly. The piston is provided with an upwardly ranging stem 25^b having a guide 25^a at its upper end. This space, in conformity with a salient feature of my invention, is filled with oil or other incompressible fluid, before the device is put into use. Said piston is of the spool type, providing an internal reservoir 27. A non-return valve 28 is preferably provided between the space 26 and said reservoir 27, to allow fluid to pass readily from the reservoir into space 26, while preventing return flow. The nonreturn valve is placed in a fluid course 28^b provided centrally of the piston. This fluid course provides for flow of fluid from space 27 to space 26 while the valve prevents return flow through such course. The course opens into space 27 at ports 28^a provided in stem 25^b. A small bypass duct 29 is provided so that fluid may slip from space 26 to space 27 only very slowly so that the piston can descend only at a very slow rate.

A spring 30, below the piston, urges the piston constantly upwardly. Thus the piston is held up against the pointed end of the head of the mandrel to hold the shoulder

thereof in abutment with the spring fingers, so as to reduce lost motion to a minimum.

The operation and advantages of the device, and the novelty and usefulness of my invention will be more apparent from the following:—In Fig. 3, I have shown the tubing 32, the pump casing 33 at the end of the tubing, and the plunger assembled within the casing. In this case the plunger is so large that it cannot be moved up through the tubing. At the lower end of the pump casing there is shown a shoulder 33^a to represent any usual member within a pump casing which limits descent of the plunger.

The tube 6 is attached to the pump plunger, while the mandrel is attached to the end of the rods. When the pump is lowered into the well, the rods are later lowered until the mandrel head is forced by the spring fingers. The weight of the rods then moves upon a plunger element 35, which is loosely fitted in the tube 6 above the piston, with a strong spring 36 between the element 35 and the piston. Stops 37 and 38, respectively, on members 25^a and 35, respectively, are arranged to abut before the spring 36 is compressed unduly. The plunger then descends, allowing the spring fingers to snap into place, and the spring 36 then returns the element 35 and holds the mandrel head in place. During the slight interval that the spring 36 presses down on the piston, said piston is prevented from moving, appreciably, because of the incompressible mass of fluid below it. Spring 36 should be strong enough to force the plunger down, on its down stroke, without being compressed itself. During each up stroke of the rods, the pump plunger is lifted by coaction of the mandrel head and the spring fingers. During each down stroke, the thrust of the rods is imparted to the plunger through the incompressible body of fluid below the piston. During each down stroke, very little, if any, fluid will leak from the space 26 to the reservoir 27, but if it should, the spring under the piston will return the piston to normal position as soon as the weight of the rods is taken off of the said piston; said fluid returning easily through the non-return valve.

When it is desired to disconnect the rods from the plunger, the weight of the rods, or a part of the weight of the rods, is allowed to come upon the piston, with the plunger dropped down into the pump casing as far as shoulder 33^a. Slowly, the fluid in the space below the piston will leak out into the reservoir by escaping around the piston. After a lapse of a minute or so, the lower end of the piston strikes the member 10 at the end of the tube and the piston can go no farther. By this time the stop on the mandrel has forced the loose ring into position between the fingers. Now the rods are raised until the shoulder on the mandrel strikes the

ring. The ring begins to ascend with the rods, through the fingers. Just as the fingers snap from the ring into the conical head of the mandrel, the said mandrel may be drawn above the fingers without interengagement of the fingers and the shoulder. The rods are now free to be raised without the plunger.

It will be apparent now that I have provided a practical device for carrying out the objects of my invention, and while I have shown and described only one embodiment of my invention, numerous other embodiments will suggest themselves to the minds of those skilled in the art after they have read the foregoing, therefore I do not limit myself to any specific embodiment, except within the appended claims.

I claim:

- 20 1. In a device of the class described, interlocking members movable relative to each other in one direction for disengagement; said members arranged to interlock when moved relatively in the other direction, a cylinder carried by one of said members, a piston movable by the other of said members; said piston and cylinder coacting to provide a fluid space which decreases in volume when the members are moved for disengagement, and a non-return valve between said piston and said cylinder permitting flow of fluid into said space when the said members are moved in the direction for interlocking.
- 25 2. In combination with a pump and rod attachment having relatively movable parts movable relatively in one direction for disengagement and movable relatively in the other direction for interengagement, and a piston and cylinder providing an oil space resisting rapid disengaging movement of said parts.
- 30 3. In a device of the class described, a pair of interlocking members movable toward each other for disengagement, and means for preventing rapid disengaging movement of the members, while permitting relatively slow disengaging movement.
- 35 4. In combination with a pump plunger, a pump cylinder and a valve coacting to lift fluid on one stroke whereby the plunger offers maximum load on its up-stroke, a rod for lifting said plunger, a rod-to-plunger attachment between said rod and plunger permitting of disengagement of the rod and 55 plunger by downward movement of the rod with regard to the plunger; and means permitting of slow movement of the rod toward the plunger while substantially resisting rapid movement of the rod with 60 regard to the plunger.
- 40 5. In a pump and rod attachment of the class described, a tube, inwardly projecting latches to said tube, a mandrel movable downwardly in said tube to pass said 65 latches; said rod provided with a shoulder arranged to interlock with the latches normally preventing upward movement of said mandrel relative to said tube, a traveling member loosely fitted on said rod above said 70 shoulder, and a stop for limiting upward movement of said traveling member with regard to said mandrel; said member movable to position between said latches to prevent interengagement of the latches and the 75 shoulder of the mandrel whereby said mandrel may be moved upwardly beyond said latches when said traveling member is between the latches.
- 45 6. An attachment as in claim 5 and further including; means for resisting rapid downward movement of said mandrel with regard to said tube while permitting of slow downward movement of said mandrel with regard to said tube. 80
- 50 7. In a device of the class described, a tube having inwardly bowed spring fingers, a mandrel provided with a head movable downwardly through said tube past said fingers; said fingers normally preventing 85 such return movement, and means whereby further continued descent of said mandrel will render said fingers ineffective in preventing return movement of said mandrel.
- 55 8. A device as in claim 7 and further including; means preventing rapid downward movement of said mandrel in said tube; said means permitting of slow downward movement in said tube. 90
- 60 9. In a device of the class described, a pair of interlocking members relatively movable in one direction for disengagement and relatively movable in another direction for inter-engagement, and hydraulic means for preventing rapid movement while permitting of slow movement in one such direction. 100
- 65 10. In a device of the class described, a pair of interlocking members relatively movable in one direction for disengagement and relatively movable in another direction for inter-engagement, and hydraulic means for preventing rapid movement while permitting of slow movement in one such direction. 105
